(57) CLAIM

The ornamental design for a nail accessory display and storage organizer, as shown and described.

DESCRIPTION

FIG. 1 is a perspective view from the front of the nail accessory display and storage organizer;
FIG. 2 is a perspective view from the rear thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a side elevational view from the right thereof;
FIG. 8 is a side elevational view from the left thereof;
FIG. 9 is a perspective view from the front thereof, in the open position, with the broken line showing environmental structure only and not forming a part of the design; and,
FIG. 10 is a perspective view from the front thereof, in the open position, showing the underside.
